UNITED STATES PATENT OFFICE.

VIRGIL E. MORSE, OF SHELTON, CONNECTICUT.

HOOK AND EYE.

No. 901,987.

Specification of Letters Patent.

Patented Oct. 27, 1908.

Application filed November 11, 1907. Serial No. 401,663.

To all whom it may concern:

Be it known that I, VIRGIL E. MORSE, a citizen of the United States, residing at Shelton, in the county of Fairfield, and State 5 of Connecticut, have invented a new and useful Improvement in Hooks and Eyes; and I do hereby declare the following, when taken in connection with the accompanying drawings and the letters of reference marked 10 thereon, to be a full, clear, and exact description of the same, and which said drawings constitute part of this specification, and represent, in—

Figure 1 a side view of a hook and eye 15 constructed in accordance with my invention and showing the hook engaged with the eye. Fig. 2 a top view of the same. Fig. 3 a top or plan view of the hook. Fig. 4 a plan view of the eye detached. Fig. 5 a sectional 20 view showing a modified arrangement of the attaching loops for the hook member.

This invention relates to an improvement in hooks and eyes, and particularly to the smaller hooks and eyes made from wire and 25 adapted especially for garments, the object being a simple construction which not only forms a hook, but also a spring shoulder therefor in the nature of a ball and socket fastener, so that after the hook is engaged 30 with the eye, a shoulder will be snapped into engagement with the eye whereby the hook is locked in position, thus avoiding accidental disengagement; and the invention consists in the construction hereinafter de- 35 scribed and particularly recited in the claims.

In carrying out my invention I employ an eye 2 of usual construction embodying a circular portion and small loops 3 by which it may be secured to a garment. The hook 40 is also formed from a single piece of wire having attaching loops 4 at opposite ends. The wire is doubled upon itself and from the loops extends upward and rearward forming a short hook 5. The bill 6 is turned 45 abruptly forward in a plane parallel with the plane of the loops and corresponds in length substantially to the diameter of the eye 2. The end of the bill is then turned down at a substantial right angle forming a 50 shoulder 7 and the central portion of the wire bent to form an attaching loop 8. The hook 5 is first engaged with the outer portion of the eye 2 in the usual manner of hooks and eyes. Then the shoulders 7 are 55 forced downward between the converging ends of the eye member adjacent to the at-

taching loops 3. By this construction a very short hook is employed, that is, the engagement with the eye is made at a point close to the attaching loops 4 of the hook, and so 60 that when attached the overlapping edges of the fabric will be held together much closer than when the hook is formed with a long bill beneath which the eye passes, and when the point of engagement with the eye 65 is at a considerable distance from the attaching loops of the hook member. As the shoulders 7 are forced between the converging sides of the eye the wire of the eye will yield so that the engagement at that end of 70 the hook member is on the order of a ball and socket snap.

As shown in Fig. 1 of the drawings, the attaching loop 8 of the hook member is turned inward but it might be turned outward as shown in Fig. 5 of the drawings. The shape or form of the attaching loops 75 may, of course, also be modified as desired.

I claim:—

1. The herein described hook for hooks 80 and eyes formed from a single piece of wire having a loop formed in the center thereof and at opposite ends of the wire, the intermediate portion of the wire bent into U-shape 85 extending obliquely upward and rearward forming a short hook, and thence forward in a plane parallel with the plane of the loops and thence straight downward forming a locking shoulder at the forward end of the bill. 90

2. The herein described hook for hooks and eyes formed from a single piece of wire having a loop formed in the center thereof and at opposite ends of the wire, the intermediate portion of the wire bent into U-shape 95 extending obliquely upward and rearward forming a short hook, and thence forward in a plane parallel with the plane of the loops and thence straight downward forming a locking shoulder at the forward end 100 of the bill, and an eye with which the said hook may engage and between the sides of which the shoulder of the hook may pass, substantially as described.

In testimony whereof, I have signed this 105 specification in the presence of two subscribing witnesses.

VIRGIL E. MORSE.
